Geo. S. Brown.

Inventor:

August E. Kivikink
By Wilkinson, Husley, Raymond & Atty.

UNITED STATES PATENT OFFICE.

AUGUST E. KIVIKINK, OF INDIANA HARBOR, INDIANA.

ANTIGLARE SHIELD FOR AUTOMOBILES.

Application filed January 2, 1924. Serial No. 683,907.

To all whom it may concern:

Be it known that I, AUGUST E. KIVIKINK, a citizen of the United States, residing at Indiana Harbor, in the county of Lake and State of Indiana, have invented certain new and useful Improvements in Antiglare Shields for Automobiles, of which the following is a specification.

This invention relates to an anti-glare shield for automobiles of the type in which a transparent curtain of flexible material is wound upon a roller for retiring it from position and storing it while not in use. Shields of this kind employing celluloid or equivalent material for their transparent curtains, are greatly impaired in a comparatively short time by the abrasion of the celluloid upon itself, and particularly with intervening dust as the curtain is rolled and unrolled.

The object of the present invention is to avoid this disadvantage, and the invention proceeds upon the principle of winding with the curtain a soft fabric or other flexible material which will keep the convolutions of the curtain from contacting one with another; means being provided for automatically gathering and storing the lining material in a position which will prevent its interference with the use of the curtain when the curtain is unwound, and paying back the liner to the curtain roll as the curtain is rewound. In the preferred embodiment of the invention, a spring roller is employed for winding the curtain and liner together, and a second spring roller for gathering and storing the liner when not in use; the spring of the curtain roller being of a capacity which enables it to dominate the spring of the lining roller and cause unwinding of the latter as the liner is required to be wound upon the former.

Another object of the invention is to provide improved means for retaining the pull cord and through it the free end of a curtain when the curtain is unwound and in position of use, such means being designed with a special view of rendering it automatic in engaging the curtain cord by the mere act of pulling the cord and through it the curtain until the latter reaches the unwound position, and for convenient release of the cord when it is desired to have the curtain automatically retired from position of use.

In the accompanying drawing—

Figure 1 is an elevational view showing the fragments of an automobile windshield, and having associated therewith an anti-glare shield constructed in accordance with the present invention.

Figure 2 is a section on the line 2^x—2^x of Figure 1, on an enlarged scale.

Figure 3 is a horizontal section in a plane coinciding with the axes of the two spring rollers, also on an enlarged scale.

Figure 4 is a top plan view of the releasable detent which engages and retains the pull cord.

Figure 5 is a side view of the same.

Figure 6 is a section on the line 6^x—6^x of Figure 4; and

Figure 7 is a view similar to Figure 1 illustrating a modified arrangement of shield in which the invention may be embodied.

1 represents the windshield of an automobile, and 2 an anti-glare curtain adapted to be drawn to a position over a portion of the wind-shield which will adapt the curtain to intercept the driver's line of vision, and by coloring, or other condition in the curtain, tempering the light from an automobile traveling in the opposite direction. It has heretofore been proposed to mount such a curtain through means, such as the roller 3 (Figures 2 and 3) in a housing 4 in order to retire the curtain from position of use when not needed, and hold it within convenient reach for instant use when needed, such an arrangement being shown in United States Letters Patent No. 1,468,118, issued September 18, 1923, jointly to this inventor and Emil Nilson, but such method of storing the curtain has been found to impair the surface of the curtain owing to the accumulation of dust upon the surface, which, when the curtain is wound up, develops serious abrasion between the convolutions of the curtain on the roll. In order to remedy this defect, the present invention employs, in addition to the curtain 2, a liner 5, preferably of soft fabric, but which may be of any suitable material capable of winding upon the roller 3 with the curtain 2, and this liner, while attached at one end to the roller 3, has its opposite end attached to an independent roller 6 which pays out the liner as it is wound upon the roller 3, and

- thus serves the purpose of introducing between the convolutions of the curtain 2 a packing material which avoids the abrasion referred to.
5. Rollers 3 and 6 are preferably provided, respectively, with winding springs 7 and 8, which normally seek to revolve the rollers in the direction to wind the flexible members secured thereto, so that roller 6 is positively wound and caused to gather up the liner 5 as the curtain 2 is unwound; but the spring 7 is materially stronger than the spring 8, so that when curtain 2 is released to the winding action of the roller 3, said 70 spring 7 will overcome the spring 8 of the roller 6 and draw the liner 5 from the latter as it is needed. A secondary advantage in the described arrangement, wherein the liner 5 is under tension at all times between 10 the two rollers, is that it insures a tight and smooth winding of the curtain 2 upon the roller 3 in addition to supplying the packing for the wound curtain, and thus further insures the lasting quality of the shield. As 15 shown in Figure 3, spring 7 within the roller 3 is wound in the opposite direction from the spring 8 in the roller 6, in order that the rollers may act to best advantage in functioning as described.
20. The described arrangement is adapted for use in the housing 4, from which the curtain 2 is drawn downward from the roller 3 as shown in Figures 1 to 3, or the several features of the invention may be embodied 25 in an arrangement in which a roller housing 4^a is mounted on a vertical axis, curtain 2^a moves horizontally with relation thereto, and has traveling support at its upper edge through means of an arm 9.
30. In order to control the curtain 2 a pull cord 10 is attached to the lower binder 11 of the curtain, and this cord works through an automatic gripper 12, comprising a stationary jaw 13 and a movable jaw 14, the 35 cord 10 being provided with an enlargement 15, preferably in the form of a sphere, which is adapted to force its way past the jaws 13, 14 by momentary displacement of the movable jaw 14, and thereafter be engaged by the jaws to resist upward movement of the curtain under the influence of its roller 3. Jaw 14 is resiliently pressed to its duty by means of a spring 16, which 40 spring develops in the jaw 14 ample resistance to the spreading of the jaws by the enlargement 15 under any upward pull which the spring roller 3 is capable of exerting, but with a force that yields to the superior spreading effort of the enlargement 15 under a manual pull upon the cord 10 in a downward direction. With this arrangement, when it is desired to retire the curtain from position of use, it is simply necessary to manually displace the movable 45 jaw 14 in opposition to the spring 16, and this is accomplished by pressing upon a thrust member 17, in the form of a yoke, connected to jaw 14, through means such as screws 18 that work in slots in the frame 19, one of which slots is shown at 20 in Figure 5 while the other is shown at 21 in Figure 6. Yoke 17 is held in assembly with the frame 19 while permitting relative movement thereon, through means of slot and pin connection 22 (Figure 5). 75
- I claim:
1. In an anti-glare shield, a curtain, a roller for winding said curtain, a second roller, and a curtain liner wound upon said second roller and connected for winding 80 jointly with the curtain upon the curtain roller; each of said rollers being provided with means rendering it independently self winding as the element wound thereon is relieved of tension. 85
2. In an anti-glare shield, a curtain, a roller for winding said curtain, a second roller, and a curtain liner wound upon said second roller and connected for winding 85 jointly with the curtain upon the curtain roller; said second roller being provided with a spring which causes the liner to be wound thereon as the curtain is unwound from the curtain roller. 90
3. In an anti-glare shield, a curtain, a roller for winding said curtain, a second roller, and a curtain liner wound upon said second roller and connected for winding 95 jointly with the curtain upon the curtain roller; said second roller being provided 100 with a spring which causes the liner to be wound thereon as the curtain is unwound from the curtain roller; and the curtain roller being provided with a spring which revolves it in the direction of winding and 105 overcomes the spring of the liner roller in winding the curtain and liner jointly. 105
4. In combination with a curtain, a pull cord, an enlargement on said cord, and a gripper, comprising jaws between which 110 said cord is free to travel; said jaws being relatively movable to enlarge the space between them, and said enlargement and jaws being constructed to coat and force the jaws apart and pass the enlargement between them in the movement of the enlargement in one direction and to engage said enlargement and resist its movement in the opposite direction. 115
5. A gripper for pull cords, comprising 120 fixed and movable jaws, and a spring for resiliently pressing the movable jaw toward the fixed jaw; said movable jaw having a camming surface which renders it displaceable under the action of an enlargement on 125 the cord moving between the jaws in one direction, but said jaws being adapted to resist passage of said enlargement in the opposite direction. 125
6. A gripper for pull cords, comprising 130

fixed and movable jaws, and a spring for resiliently pressing the movable jaw towards the fixed jaw; said movable jaw having a camming surface which renders it displaceable under the action of an enlargement on the cord moving between the jaws in one direction, but said jaws being adapted to resist passage of said enlargement in the opposite direction; and said movable jaw being provided with a thrust member through which it may be positively displaced to release the enlargement.

Signed at Chicago, Illinois, this 11th day of December, 1923.

AUGUST E. KIVIKINK.
